(57) **CLAIM**

The ornamental design for a “golf towel bag,” as shown.

DESCRIPTION

FIG. 1 is a perspective view of a golf towel bag showing my new design;

FIG. 2 is front elevational view thereof;

FIG. 3 is rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The golf club inserted in a panel golf sleeve is shown in broken lines for illustrative purposes only and form no part of the claimed design.
